UNITED STATES PATENT OFFICE.

CHARLES ALGERNON PARSONS, OF NEWCASTLE-UPON-TYNE, ENGLAND.

PROPELLER.

1,107,101.

Specification of Letters Patent. Patented Aug. 11, 1914.

Application filed July 25, 1913. Serial No. 781,202.

To all whom it may concern:

Be it known that I, CHARLES ALGERNON PARSONS, a subject of the King of Great Britain and Ireland, residing at Heaton Works, Newcastle-upon-Tyne, in the county of Northumberland, England, have invented certain new and useful Improvements in and Relating to Propellers, of which the following is a specification.

10 This invention relates to improvements in propellers and particularly to propellers designed for propulsion of modern high speed vessels.

It is well known that in order to carry the 15 thrust necessary for such high speed vessels it is essential that the projected blade area of the propeller shall represent from 50 per cent. to 90 per cent. of the disk area of the propeller. Such propellers, however, are 20 less efficient at all the low speeds than the propellers with narrower blades of the type usual in former years.

The object of the present invention is to 25 provide a propeller of improved form which, when applied to the modern conditions for high speed vessels shall give a greatly increased efficiency. This object is attained by giving the leading edges of the propeller blades a scimitar or thrown-back 30 configuration, and combining this configuration with a sufficiently large blade thrust area of from 50 per cent. to 90 per cent. of the disk area as above described. Scimitar blades have been previously proposed, but 35 without success, and my invention requires a large thrust area in addition to the specially shaped edge. A propeller according to this invention therefore has blades of large area and a leading edge to each blade 40 so shaped as regards the whole or the outer part only thereof that the component of the velocity of entry of the edge or of the outer part thereof into the surrounding medium in the direction normal to the edge is ap- 45 proximately constant. It is generally ad- 50 visable that this constant velocity shall be kept small especially over the outer edge of the blade, and should not exceed one-third of the peripheral velocity of the tip of the blade. I have found by experiment that one of the chief causes of loss in cavitation is the formation of vortex spirals produced by the flow of water from the pressure to the

suction side over the outer portions of a propeller blade. These spirals form a sink of 55 energy drawn from the propeller blade which energy is absorbed by the eddying motion of the fluid upon the extinction of such vortices. The shape of the leading edge of a propeller blade is therefore of 60 great importance in regard to the efficiency of a propeller. I have further found by experiment that the shaping of the whole or the outer part of the leading edge of a propeller blade in the foregoing manner owing 65 to the more gradual cutting of the edge through the fluid which is thereby obtained, diminishes the formation of such spirals and the consequent loss of energy.

Referring now to the accompanying drawings:—Figure 1 illustrates a method of setting out the projection of the edge. Fig. 2 shows the projected view, and expanded view of one blade, of a propeller constructed in accordance with the invention. Fig. 3 75 shows a plan view, Fig. 4 a longitudinal section through the boss and one of the blades, and Fig. 5 sections of the blade on various radii of the propeller shown in Fig. 2.

The value of the constant component of 80 the velocity of the blade normal to the leading edge may be chosen to suit the conditions of the case, but generally it is preferred to make this not more than one-third of the tip speed of the propeller. The constant 85 component of the velocity into the surrounding medium in the direction normal to the edge of the blade is the product of the velocity in a helical direction of any point on the curve multiplied by the cosine of the angle 90 α which the true curve makes with the perpendicular from that point to the axis of the propeller. The value of $\cos \alpha$ can be expressed in terms of the tangent of the projected angle ϕ , and the value of the component 95 is then given by the expression,

$$\frac{4\pi^2r^2 + p^2(1-S)}{\sqrt{4\pi^2r^2 + p^2}} \times \frac{1}{\sqrt{1 + \left(1 + \frac{p^2}{4\pi^2r^2}\right) \tan^2 \phi}} = C \quad 100$$

where r =the radius vector O P, where p =the pitch, where s =normal slip ratio expressed as a fraction and where ϕ = the angle between the projected curve shown in Fig. 1 and any 105 of the lines O P. By these means the value

of ϕ for any point on the curve is easily calculated for which purpose the foregoing expression may be rewritten.

$$5 \quad \tan. \phi = \frac{2\pi r}{C} \sqrt{\frac{(4\pi^2 r^2 + p^2(1-S))^2}{(4\pi^2 r^2 + p^2)^2} - \frac{C^2}{4\pi^2 r^2 + p^2}}$$

10 A sufficiently close approximation to the curve of the leading edge of the blade may be obtained by neglecting the slip S in which case the following simplified expression may be used.

$$\tan. \phi = \frac{2\pi r}{C} \sqrt{1 - \frac{C^2}{4\pi^2 r^2 + p^2}}$$

15 Let ϕ be the angle between any radius vector $O P$ and a radial line $X X'$ passing through the point at which the leading edge joins the boss of the propeller as shown in

20 Fig. 1, then since $\tan \phi = \frac{rd\Theta}{dr}$ by dividing

25 by r the value of $\frac{d\Theta}{dr}$ is obtained in terms of r at any point, and the value of Θ in terms of r can be deduced therefrom by integration. The curve of the projected leading edge is plotted as shown in Fig. 1 by the intersection of a series of equidistant concentric circles with radii drawn for the 30 corresponding values of Θ determined as above.

35 The extreme diameter of the propeller, pitch ratio, projected surface ratio, diameter of the boss and number of blades can be varied as desired and are determinable in the usual way, as for propellers of normal shape. The curve of the leading edge having been determined as above, the trailing edge can be drawn by striking a fair curve 40 from the tip of the propeller to the boss in such a manner as to give the necessary projected area to suit the thrust and speed for which the propeller is designed.

45 A three-bladed propeller in accordance with this invention is shown in Figs. 2 to 5 of the accompanying drawings, Fig. 2 showing a projected view of the three blades on a plane at right angles to the axis of rotation also an expanded view of the upper blade 50 indicated by dotted lines. This propeller has a uniform pitch equal to its diameter, and in Fig. 3 the plan of one blade is shown, together with the projections of the pitch helices which would be traced upon the surfaces indicated by the semi-circles numbered 55 1 to 8 in Fig. 2. Fig. 4 shows a section through the boss together with a section

through one of the blades upon a line drawn from the boss to the tip approximately through the middle of the blade. A side view of the upper blade is also shown in projection.

65 In Fig. 5 the true sections of the blade upon surfaces indicated by the semi-circles 2 to 8 of Fig. 2 are shown, the sections being numbered to correspond with the surfaces upon which they are taken.

70 The formation of blade as hereinbefore described induces a more regular stream line motion of the fluid around the blade, and thus diminishes its resistance as a body moving through the fluid. Such a propeller has a considerably improved efficiency at high 75 speeds, and high thrusts with which cavitation usually occurs, but I also find that this improvement is obtained at low speeds and small thrusts at which no cavitation occurs.

75 With a propeller blade constructed in the foregoing manner a line drawn approximately through the middle of the blade 80 slopes back in a projected view at a large angle from the radius, and this median line in the projected view may be approximately an equi-angular spiral. The shape of the blade may be modified for the sake of 85 strength in the portions near the boss without appreciably affecting the efficiency of the propeller, provided that the leading edge is substantially shaped in the above manner at its outer portion, where the peripheral 90 velocity is high. Also other modifications may be made, for instance, the propeller may be of uniform or varying pitch, or its generating line may be inclined backward or forward to the axis of the propeller. 95

Having now fully described and ascertained my invention and in what manner the same is to be performed, I declare that what I claim is:

100 A propeller having blades of large area and a leading edge to each blade so shaped as regards the whole or the outer part only thereof that the component of the velocity of entry of the edge or of the outer part thereof into the surrounding medium in the 105 direction normal to the edge is approximately constant, substantially as described.

110 In testimony whereof I affix my signature in presence of two witnesses.

CHARLES ALGERNON PARSONS.
